UNITED STATES PATENT OFFICE.

JOHN C. GRIESSEL, OF POTTSVILLE, PENNSYLVANIA.

AMUSEMENT DEVICE.

1,220,980.

Specification of Letters Patent. Patented Mar. 27, 1917.

Application filed July 5, 1916. Serial No. 107,635.

To all whom it may concern:

Be it known that I, JOHN C. GRIESSEL, a citizen of the United States, residing at Pottsville, in the county of Schuylkill and 5 State of Pennsylvania, have invented new and useful Improvements in Amusement Devices, of which the following is a specification.

Broadly stated, this invention comprehends the provision of an amusement device, by means of which the national game of base ball can be scored, although it is primarily intended for use at carnivals, picnic grounds, and other amusement places, 10 where prizes are given to persons obtaining a certain number of "hits" with a given number of balls, or striking out the "batter" with the least number of balls.

The nature and advantages of the invention will appear as the following description is read in connection with the accompanying drawings, wherein the preferred embodiment of the invention is illustrated, 15 the invention however residing in the scope 20 of what is claimed.

In the drawings forming part of this specification like numerals of reference indicate similar parts in the several views and wherein:—

30 Figure 1 shows the relative position of the figures.

Fig. 2 is a rear view.

Fig. 3 is a sectional view taken on line 3—3 of Fig. 2 looking in the direction of the 35 arrow.

Fig. 4 is a rear elevation of the figure representing the "catcher".

Fig. 5 is a vertical sectional view therethrough.

40 Fig. 6 is a side elevation.

Referring more particularly to the drawings in detail A and B are two figures representing base ball players, the figure A being indicative of the "batter", while the figure B is indicative of the "catcher". The figures can be constructed from any suitable material, and are preferably made up of a plurality of wooden sections, each comprising a body section 10, to the lower edge 45 of which is secured the sections 11 representing the limbs of the player, while the sections 12 represent the arms, the body section 10 of course being provided with a head portion 13. The sections are formed 50 and joined together in the manner to permit the figures to be conveniently boxed for

shipping, while the relative dimensions of the sections produce figures of life size. Both of the figures A and B respectively will be suitably padded and uniformed. 60

In the hands 12 of the figure A is a bat 14, which latter is pivotally mounted for swinging movement, preferably in a horizontal plane. Arranged at the opposite sides of the bat 14 are springs 15 which have 65 their corresponding outer ends secured to the bat in any suitable manner, for the purpose to be hereinafter described, the opposite ends of the springs being secured to an appropriate part of the figure A. The bat 70 is normally held stationary directly in front of the figure A by means of a trigger, which as shown in this instance consists of an arm 16 pivoted at one end upon the figure A and provided with an offset terminal 17 adapted 75 to be received within a screw eye 18 in the bat. The figure A is preferably supported by the headed elements 19 slidably fitted within suitable guides 20 on the limbs 11 and adapted to be driven into the ground 80 or surface. The figure A is preferably supported with one foot slightly in advance of the other representing the batter in his position at the "home plate".

The "catcher" B is supported in a similar 85 manner immediately at one side of the "batter", except that the "catcher" is further braced by means of the rod 21. The head portion 13 of the "catcher" is covered with a mask 22, while covering the body 90 section 10 is a chest protector 23. Concealed under the uniform and chest protector of the "catcher" is a strike board 24, of suitable dimensions, the board being yieldably mounted and normally held in its 95 foremost position by means of the springs 25. Signaling devices of any suitable character, are indicated at 26 and are disposed in the path of movement of the strike board 24 to be operated thereby when the board is 100 moved to its rearmost position. The arms 12 of the "catcher" are pivotally mounted upon the opposite sides of the body section 10 and normally disposed in a horizontal position, the arms being connected to the 105 offset terminals 27 of a yoke 28, which latter is pivotally mounted on the body section 10 at the rear thereof, and operatively connected with the head 13 of the "catcher" by means of the rod 29 for the purpose to be 110 hereinafter described.

In use, the figures A and B are arranged

in their relative playing positions in the manner illustrated in Fig. 1, while the playing field is marked off along the first and third base lines from the "home plate" 5 C. The player then takes his position in advance of the "batter" at a predetermined distance therefrom, and delivers the balls to the "batter." If the device is used for playing the national game of base ball, it is the object of the player to strike the "batter" out, which is accomplished by hitting the bat 14 with a thrown ball in a manner to release the trigger 16 but at the same time prevent the ball from being hit into fair territory. Of course the impact of the ball against the bat moves the latter rearwardly, permitting the trigger 16 to gravitate to an inoperative position, while the forward spring 15 is placed under 10 tension. The springs 15 then function to swing the bat in a horizontal plane, which gives the "batter" the appearance of striking at the ball, and is recorded as a "strike." The player may miss the bat entirely, but if the throw is in line for a "strike," that is to say within a given area either above or below the bat 14, the ball will strike the breast protector 23 of the catcher, the force of the impact driving the strike board 24 15 rearwardly to sound the signals 26, which is evidence of a "strike." If however, the pitch is wild, that is to say that the ball is not brought in contact with either the bat or the breast protector 23 it is recorded a 20 "ball," four "balls" entitling the "batter" to a base, while three "strikes" retires the "batter" as in the well known game of base ball. The player however in attempting to strike the "batter" out will often 25 strike the bat 14 with the ball in a manner whereby the ball will be driven into fair territory, and which play is recorded a "hit" entitling the "batter" to a base. This system of scoring is continued until 30 the player succeeds in securing three "outs," when the player of the opposition takes his place in the "pitcher's" box.

However the device herein illustrated is primarily intended for use at carnivals and 35 other amusement places, wherein a predetermined number of balls are sold for a certain sum, and prizes given to the person obtaining a certain number of "hits" with a given number of balls, or the person striking out the "batter" with the least number of balls, which is of course three. The player delivers the ball to the "batter," from the requisite distance, and if he succeeds in hitting the bat with the ball in a 40 manner so that the ball will be driven in fair territory it is recorded a "hit." If on the other hand he succeeds in hitting the bat to cause the latter to swing upon its pivot, without driving the ball into fair territory 45 this is recorded a "strike." Again, if the

pitch is within a certain area, causing the ball to strike the breast protector and operate the signal 26 through the instrumentality of the strike board 24, a "strike" is recorded for the player. Should the player 50 make a wild pitch striking the mask 22, the head 13 of the "catcher" will be forced backwardly upon its pivot 30, whereupon the yoke 28 through the instrumentality of the connecting rod 29, will be moved upon 55 its pivot, thereby forcing the arms of the "catcher" upwardly and resembling an attempt to catch the ball. The weight of the arms will automatically return the parts to their normal position. It might here be 60 stated that the terms "hit" and "strike" as used in the claims are to be interpreted within the limits of the definition of these terms as hereinabove outlined.

While it is believed that from the foregoing description the nature of the invention will be readily apparent, I desire to have it understood that what is herein shown is merely illustrative of one embodiment of the invention, to which I do not limit myself, and that such changes in the construction and arrangement of parts may be resorted to when desired as fall within the scope of what is claimed.

What is claimed is:

1. An amusement device comprising means including a bat mounted for horizontal swinging movement, and disposed in the path of perfectly thrown balls for determining "hits," and means for normally holding the bat stationary and adapted to be released upon movement of the bat in one direction. 95
2. An amusement device comprising a bat mounted for swinging movement and disposed in the path of perfectly thrown balls, for determining "hits," means normally holding the bat stationary and adapted to be released upon movement of the bat in one direction, and resilient means operable to swing the bat in reverse directions upon release of the latter. 100
3. A device of the class described comprising a figure representing a "batter," and, a figure representing a "catcher" disposed in juxtaposition to said "batter," the last mentioned figure having a movably mounted head and arms, and means connecting said parts to automatically move said arms upward when said head is moved rearwardly. 115
4. An amusement device comprising a figure representing a batter, and a figure representing a catcher disposed in juxtaposition to the batter, a bat associated with the batter for swinging movement and disposed in the path of perfectly thrown balls, a strike board pivoted on the figure representing the catcher for rocking movement, and an audible signal normally spaced from each end of said board and operable when the board is brought into engagement therewith. 120
5. An amusement device comprising a figure representing a batter, and a figure representing a catcher disposed in juxtaposition to the batter, a bat associated with the batter for swinging movement and disposed in the path of perfectly thrown balls, a strike board pivoted on the figure representing the catcher for rocking movement, and an audible signal normally spaced from each end of said board and operable when the board is brought into engagement therewith. 125
6. An amusement device comprising a figure representing a batter, and a figure representing a catcher disposed in juxtaposition to the batter, a bat associated with the batter for swinging movement and disposed in the path of perfectly thrown balls, a strike board pivoted on the figure representing the catcher for rocking movement, and an audible signal normally spaced from each end of said board and operable when the board is brought into engagement therewith. 130

5. An amusement device comprising a figure representing a batter, and a figure representing a catcher disposed in juxtaposition to said batter, a bat associated with the batter for swinging movement and disposed in the path of perfectly thrown balls, means normally holding the bat stationary, a strike board yieldably supported upon the figure representing the catcher, an audible signal supported upon said figure at the rear of said board and operable with the yielding of the latter, said figures being padded, and said strike board being wholly concealed from view by the uniform of its associated figure.
- 10 6. An amusement device comprising a figure representing a batter, and a figure representing a catcher disposed in juxtaposition to the batter, a bat associated with the batter for horizontal swinging movement and disposed in the path of perfectly thrown balls, 20 and means for normally holding the bat stationary, a strike board pivotally mounted upon the figure representing the catcher for rocking movement, yieldable means normally holding said board in a vertical position, and 25 audible signals supported at the rear of the board and operable when the board is brought into engagement therewith.

In testimony whereof I affix my signature.
JOHN C. GRIESEL
